UNITED STATES PATENT OFFICE.

JACOB E. C. JACOBSEN, OF NYACK, NEW YORK.

DESIGN FOR A COMBINATION-TOOL.

42,805.

Specification for Design.

Patented July 16, 1912.

Application filed March 27, 1912. Serial No. 686,629. Term of patent 3½ years.

To all whom it may concern:

Be it known that I, JACOB E. C. JACOBSEN, a citizen of the United States, residing at Nyack, New York, have invented a new, original, and ornamental Design for a Combination-Tool, of which the following is a specification, reference being had to the accompanying drawing, forming a part hereof.

The design resides in the general configuration comprising a head A, a crescent shaped device B, an intermediate connecting rod C, and a terminating end D, extending beyond the crescent and between its points.

The tool is adapted for use as a hammer, a staple lifter, a tack lifter, and a screwdriver.

I claim—

The ornamental design for a combination tool, as shown and described.

In testimony whereof, I affix my signature in presence of two witnesses.

JACOB E. C. JACOBSEN.

Witnesses:

CHAS. SEGERSTEN,
ALFRED FRITZ.
